UNITED STATES PATENT OFFICE.

SAMUEL WATERBURY, OF SCHENECTADY, NEW YORK.

CIRCUIT-BREAKER.

No. 825,098.

Specification of Letters Patent.

Patented July 8, 1908.

Application filed September 23, 1904. Serial No. 225,635.

To all whom it may concern:

Be it known that I, SAMUEL WATERBURY, a citizen of the United States, and a resident of Schenectady, in the county of Schenectady and State of New York, have invented a new and Improved Circuit - Breaker, of which the following is a full, clear, and exact description.

My invention relates to circuit-breakers, and more particularly to those which may be operated both manually and automatically, its principal objects being to secure independence between the two operating mechanisms, so that the closure of the circuit by hand will not interfere with its again automatically opening, and to otherwise improve the apparatus.

Reference is to be had to the accompanying drawings, forming a part of this specification, in which similar characters of reference indicate corresponding parts in all the figures.

Figure 1 shows one embodiment of my invention in front elevation, parts being broken away. Fig. 2 is a side elevation thereof. Figs. 3 and 4 are similar views with the elements occupying different positions. Fig. 5 is a horizontal section on the line 5 5 of Fig. 1. Fig. 6 is a perspective view of the 30 core operating within the coil. Fig. 7 is an enlarged detail, in side elevation, of another form of the upper contact members. Fig. 8 is a horizontal section therethrough on the line 8 8 of Fig. 7, and Fig. 9 is a sectional detail on the line 9 9 of Fig. 7.

10 designates a base of suitable size and form and of some insulating material upon which are mounted brackets 11 11, having lower flanges 12. Through these flanges extend oppositely-projecting pivot-pins 13, the outer ends of which are threaded to receive retaining-nuts 13^a. Movable about the pins 13 are contact-arms 14, which may be of any desired number, there being two shown in the present instance, the apparatus serving as a two-pole breaker. The arms are connected by an insulating-block 15, they being secured at each side thereof by flanges 16, through which extend screws 16^a. The outer side of each of the arms is preferably inclined at 17 and operates against a similarly-inclined metallic spring contact member 18, preferably carried by the bracket 11. The upper extremity of each arm coacts with a second contact member 19. This, as illustrated, is laminated, it being formed of sheets

of spring metal secured upon opposite sides of an arm 20, the ends of the contact member having bent portions 20^a, which press against the opposite sides of the arms. In Figs. 2 to 4 these members 19 are so situated that contact is made or broken over all the sheets simultaneously, while in Figs. 7 and 8 this making and breaking occurs successively.

At the outer side of each of the contact-arms is situated a spring 21, which may be coiled about the pin 13 for a few convolutions and then extend outwardly with angular ends 22 entering openings in the contact member 18 and in the arm, respectively. These springs, which are retained against longitudinal displacement by the nuts upon the ends of the pins, exert their tension to move the contact-arms outwardly from co-action with the relatively fixed members 18 and 19. The range of movement thus imparted is preferably such that the arms will be arrested by the springs at the desired angle of separation, and thus obviate the necessity of introducing stops or buffers. Secured to the rear of the base and connected with the contact members 18 and 19 are binding-screws or terminals 23 and 24, to which conductors may be connected.

Extending between the sides of a slot 24^a in the block 15 is a pivot-pin 25, upon which is fulcrumed a lever having an outwardly-projecting arm 26, carrying a handle 27. The inner arm 28 of the lever is preferably situated substantially at right angles to the handle portion and has pivoted upon its upper end a latch 29, the hooked end 30 of which may engage a plate 31, fixed upon the outer side of the block 15. This latch is provided with an opening, which is here shown in the form of an elongated loop 32, projecting from one side thereof, and through this opening or loop normally extends one arm 33 of a tripping-lever 34, which lies along the base and is mounted to turn in a bracket 35 and a second bracket 36. At the opposite end from the arm 35 this tripping-lever has an arm 37, which is bent at 37^a to lie between flanges 37^b of a nut 38, rotatable upon the upper threaded end of a non-magnetic rod 39. This rod extends within a coil 40, having a suitable number of convolutions and being mounted in brackets 41 and 41^a, the latter being connected with one of the brackets 11 and furnishing one terminal. Associated with this a terminal 41^b serves to deliver the

energizing-current to the coil. Fitted within the upper end of this coil is a pole-piece 42, through an opening in which the rod 39 passes, and below this pole-piece, attached to the lower end of the rod, is a core 43. As particularly shown in Fig. 6, this core is preferably made of sheet-iron or like magnetic material rolled upon itself about the rod 39 to form a cylinder, this decreasing the heating effect if the apparatus is used in connection with alternating currents and increasing the magnetic efficiency. The arm 28 has a reduced end 44, with which may coact the hooked head 45 of a latch 46, pivoted upon the bracket 35. The bracket 41 may be of iron and by its association with the core increase the magnetic effect.

To take the arc produced in breaking the circuit, and thus protect the primary contacts, secondary contacts are provided, which include a spring 47, fixed at one end at 48 upon each of the arms 20 and being bent outwardly to describe a substantially closed curve, the free end of which is adjacent to the fixed end and carries a block 49, preferably of carbon. This block is shown as secured upon the spring by a metallic member 50, extending through a transverse opening and having a head or enlargement 51, with its outer surface practically flush with that of the block, the opposite end being affixed to the spring by a screw 52. With this block co-operates a block 53, similarly secured upon a spring 54, attached at its lower end to the outer base of each contact-arm. The block 49 is preferably provided with an extension 55, overlapping and contacting with the upper side of the block 53.

Normally the elements of my improved apparatus occupy the positions more clearly indicated in Fig. 2, the contact-arms being in coaction with both of their primary contact members and the secondary members also being in contact, the parts being retained in this position by the latch 29 engaging the connecting-block, and the latch 46 co-operating with the lever. The latch 29 is maintained in engagement by the weight of the core 43, which exerts itself through the tripping-lever. This prevents accidental disengagement under shocks to which the apparatus may be subjected in use, dispenses with springs to effect the same result, and renders the mechanism more sensitive.

When an excessive current passes through the coil or one for which the coil is wound to respond, the core is drawn into the coil toward the pole-piece and presses the lower flange of the nut against the outer arm of the tripping-lever. The other arm of this lever rises and strikes the upper side of the opening in the latch 29, raising this and releasing the contact-arms, which are forced outward by their springs. After the primary contact has been broken the secondary contact members

still remain in coöperation, the metallic members 50 pressing against one another during a portion of the movement, as is shown in Fig. 3, the curvature of the spring 47 permitting this. Then as these separate the contact is passed to the overhanging portion 55 of the carbon, which takes the breaking arc without unduly destructive effect. As the contact-arms move outward the pivot-pin 25 travels upon the arc of the circle, having the pivot-pin 13 as its center. This movement lowers the position of the arm 28 with respect to the latch 46 and releases the reduced end 44 from the hooked head 45 of the latch. Thus the release of the latch 29 permits the release of the latch 46.

When it is desired to close the circuit, it is only necessary to raise the handle, the latch 29 carrying the arms with it and bringing the contact members into coaction, the parts being finally locked in their normal positions by the coaction of the latch 46 with the lever.

It will be obvious that if while the circuit were being closed a current should flow which would cause the tripping-lever to operate the latch mechanism would respond as soon as the end of the arm 33 entered the opening of the loop 32, leaving the handle in the grasp of the operator. As this entrance of the tripping-lever arm into the latch-loop occurs prior to the making of the contact, it will be evident that there can be no closure of the circuit maintained when it should be opened by the automatic mechanism. This is of particular importance, inasmuch that if there were a heavy ground serious damage might result while the operator was turning the parts to their normal position and before he could release the lever.

Having thus described my invention, I claim as new and desire to secure by Letters Patent—

1. A circuit-breaker comprising a contact-arm, a handle-lever fulcrumed upon the contact-arm and extending from its fulcrum along said arm, a latch pivoted to a relatively fixed member engaging the handle-lever, a latch pivoted to the handle-lever extension and coöperating with the contact-arm, means for releasing the first latch, and means whereby the release of the first latch may release the second latch.

2. The combination with a pivoted contact-arm, of a handle-lever fulcrumed upon the contact-arm and extending from its fulcrum along said arm, a latch pivoted upon this handle-lever extension and coöperating with the contact-arm, and a second latch engaging the handle-lever.

3. The combination with a pivoted contact-arm, of a handle-lever fulcrumed upon the contact-arm and extending from its fulcrum along said arm, a latch pivoted upon this handle-lever extension and coöperating with the contact-arm, and a second latch

pivoted to a relatively fixed member and engaging the handle-lever adjacent to the first-named latch.

4. The combination with a contact-arm, of 5 a latch therefor, a tripping-lever engaging the latch, a coil, and a core associated with the coil and supported by the tripping-lever.

5. The combination with a contact-arm, of 10 a latch therefor, a tripping-lever engaging the latch, a coil, a core associated with the coil and supported by the tripping-lever, and a second latch coöperating with the contact-arm.

6. The combination with a contact-arm, of 15 a handle-lever fulcrumed upon the contact-arm and extending from its fulcrum along said arm, a latch pivoted to the handle-lever extension and coöperating with the contact-arm, a latch for engaging the handle-lever, a 20 tripping-lever adjacent to the first latch for releasing the first latch, means for operating the tripping-lever, and means whereby the release of the first latch may release the second latch.

25 7. The combination with a contact-arm, of a handle-lever, a latch provided with an opening and pivoted upon the handle-lever and

coacting with the contact-arm, a tripping-lever extending through the latch-opening, and electromagnetic mechanism operating 30 upon the tripping-lever.

8. The combination with a contact-arm, of a handle-lever, a latch provided with an opening and pivoted upon the handle-lever and coacting with the contact-arm, a tripping-lever 35 extending through the latch-opening, a core supported upon the tripping-lever, and a coil associated with the core.

9. The combination with a base, of a metallic arm pivoted thereon, a primary metallic contact-arm carried by the base, a pair of secondary carbon contacts mounted upon the base and arm, one of the said carbon contacts having a recess in which to receive the other, and metallic contact members extending 40 through the carbon contacts.

In testimony whereof I have signed my name to this specification in the presence of two subscribing witnesses.

SAMUEL WATERBURY.
